UNITED STATES PATENT OFFICE.

THOMAS H. MARKS, OF BALTIMORE, MARYLAND.

REFRIGERATOR.

SPECIFICATION forming part of Letters Patent No. 278,158, dated May 22, 1883.

Application filed June 17, 1882. (No model.)

To all whom it may concern:

Be it known that I, THOMAS H. MARKS, of Baltimore city, State of Maryland, have invented certain new and useful Improvements 5 in Refrigerators; and I hereby declare the same to be fully, clearly, and exactly described as follows, reference being had to the accompanying drawings, in which—

Figure 1 is a perspective view, and Fig. 2 a 10 vertical longitudinal sectional view, of the device.

My present invention relates to household refrigerators, and is in the nature of an improvement upon the invention for which Letters Patent were granted me December 30, 1879, No. 223,155; and my said invention relates 15 in particular to the construction and arrangement of the ice-box; and it consists, essentially, in lining the walls of the same with a series of 20 vertical pieces of wood placed side by side, and having curved inner faces and vertical longitudinal perforations, which form pipes opening below into the storage-chamber and leading to the top of the ice-box. Wood is 25 used, as it is a practical non-conductor, and the ascending currents of air are not cooled until they enter the ice-box. This secures an important advantage, as sweating on the interior of the pipes and incident dripping back 30 of moisture are prevented.

In the drawings, A is the ice-box, having a downwardly-pitched bottom, from which a pipe leads to a drip-vessel, C, by preference within the refrigerator, though it may be below it.

G is an isolated storage-chamber for the 35 reception of fruits and other articles which do not require a very low temperature, and which by their odors would contaminate milk, cream, or butter.

F F are racks for sustaining dishes, and B is a drinking-water tank, having an outside cock, b. A similar cock, c, is provided for drawing off the drip.

From the ice-box A a chute, E, leads to the 40 base of the storage-chamber. Bars a a, having curved inner faces to sustain the ice out

of contact with them as far as possible, line the ice-box except on the side of the water-tank B, and they are provided with perforations d, which register with holes D in the bottom of 50 the ice-box. The currents of air take the direction shown by the arrows, descending through the chute E into the main storage chamber, and rising through the holes d to the top of the ice-box. In transit through the storage- 55 chamber the air becomes warmer, and in consequence takes up moisture. Were the pipes or bars a colder than the ascending currents, this moisture would condense on their inner walls and drip back into the storage- 60 chamber; but by my construction any cooling in transit is prevented, and the condensation takes place in the ice-box itself. The advantage attending this feature is obvious.

Having thus described my invention, what I 65 claim as new, and desire to secure by Letters Patent, is—

1. The ice-box A, having its inner surfaces formed of strips or blocks of wood a, placed perpendicularly side by side, each of them being provided with perforations extending the entire length thereof, as and for the purpose set forth.

2. The ice-box having inclined bottom, sides composed of vertical strips of wood perforated 75 longitudinally and having curved inner faces, the water-tank B, and outlet E, all combined and arranged as set forth.

3. The refrigerator herein described, consisting of the ice-box A, having inclined bottom, and lined on three sides with longitudinally-perforated curved front bars, a, the water-tank located on the fourth side, the main storage-chamber, and the auxiliary storage-chamber located above the main one, the wa- 80 ter-tank and storage-chamber being provided with suitable cocks, as and for the purposes set forth.

THOS. H. MARKS.
